(57) **CLAIM**

The ornamental design for an offset J-hook apparatus, as shown and described.

DESCRIPTION

FIG. 1 is a front perspective view of a left side offset J-hook apparatus of which a right side offset J-hook apparatus would be a mirror image, in accordance with an embodiment of the invention;

FIG. 2 is another front perspective view of a left side offset J-hook apparatus of which a right side offset J-hook apparatus would be a mirror image, in accordance with an embodiment of the invention;

FIG. 3 is a rear perspective view of a left side offset J-hook apparatus of which a right side offset J-hook apparatus would be a mirror image, in accordance with an embodiment of the invention;

FIG. 4 is an outside (left side) view of a left side offset J-hook apparatus of which a right side offset J-hook apparatus would be a mirror image, in accordance with an embodiment of the invention;

FIG. 5 is an inside (right side) view of a left side offset J-hook apparatus of which a right side offset J-hook apparatus would be a mirror image, in accordance with an embodiment of the invention;

FIG. 6 is a top view of a left side offset J-hook apparatus of which a right side offset J-hook apparatus would be a mirror image, in accordance with an embodiment of the invention;

FIG. 7 is a bottom view of a left side offset J-hook apparatus of which a right side offset J-hook apparatus would be a mirror image, in accordance with an embodiment of the invention;

FIG. 8 is a front view of a left side offset J-hook apparatus of which a right side offset J-hook apparatus would be a mirror image, in accordance with an embodiment of the invention; and,

FIG. 9 is a back view of a left side offset J-hook apparatus of which a right side offset J-hook apparatus would be a mirror image, in accordance with an embodiment of the invention.
